UNITED STATES PATENT OFFICE

ALBIN E. NELSON AND WILLIAM BAHR, OF DEER RIVER, MINNESOTA

VACUUM HANGER

Application filed May 28, 1931. Serial No. 540,532.

Our invention relates to vacuum hangers and particularly to that type well known in the art adapted to be stuck onto a smooth wall or glass and held thereto by suction, for 5 the holding of a card or other comparatively light object.

We are aware that somewhat similar devices have been employed for this purpose, but deem our novel construction a decided 10 improvement over such, in that a card or paper held by the same is not removable except by careful adjustment of the hanger, or rending of the article being held, which forms the principal object of our invention. 15 Other objects and advantages of the invention will appear in the following description thereof.

Referring now to the accompanying drawings, forming part of this application, and 20 wherein like reference characters indicate like parts:

Figure 1 is a perspective view of our improved hanger as it appears with a card suspended therefrom; and

25 Figure 2 is a perspective view of one of the hangers opened by stress upon same for the reception of a card, and is the better illustration of the details of construction.

1 represents a rubber vacuum hanger or 30 holder having an abnormally long shank or body portion 2, preferably terminating in an annular bead 3, with a comparatively flat or slightly rounded convex head.

The shank portion 2 is cut midway its 35 ends, substantially half its diameter, and from the extreme free end or top of the shank extends a metal pin or sprig, the head of which shows at 4 in Figure 1, and the point of which protrudes into the gap formed by 40 the cut in the shank as at 5, thus providing a sure hold to anything installed within the cut of the shank, as for example a piece of paper, or a card; the resiliency of the remainder of the shank which is intact assuring 45 the normal closing of the gap or at least impingement upon any object therein, or penetration of the sprig therethrough, and from which the object cannot be withdrawn 50 without fracture or adjustment to accomplish the opening of the gap.

It will also be apparent that the bead 3 forms a convenience in the opening of the cut, in that the finger is thereby prevented from slipping readily therefrom.

While it is obvious that various methods 55 may be resorted to in the installation of the pin or sprig in the adjustable end of the shank, we prefer to vulcanize the same therein at the time of construction of the hanger.

Having thus described one embodiment of 60 our invention, what we claim and desire to secure by Letters Patent, is:

A vacuum hanger of the type described having a protruding axial supporting shank, 65 a cut intermediate the ends of the shank transverse the axis thereof, and a sprig embedded within the outer extremity of the shank and extending into the cut.

In testimony whereof we affix our signatures.

ALBIN E. NELSON.
WILLIAM BAHR.
